(57) **CLAIM**

The ornamental design for a capsule audio & video device, as shown and described.

DESCRIPTION

FIG. 1 is a front elevational view of our new design for a capsule audio & video device;

FIG. 2 is a rear elevational view of the capsule audio & video device of FIG. 1;

FIG. 3 is a top plan view of the capsule audio & video device of FIG. 1;

FIG. 4 is a bottom plan view of the capsule audio & video device of FIG. 1;

FIG. 5 is a left side elevational view of the capsule audio & video device of FIG. 1; and,

FIG. 6 is a right side elevational view of the capsule audio & video device of FIG. 1.

The broken line shown in FIG. 4 is for illustrative purposes only and forms no part of the claimed design.
